UNITED STATES PATENT OFFICE.

EDWARD D. MEIER, OF NEW YORK, N.Y.

SUPERHEATER.

No. 895,187.

Specification of Letters Patent.

Patented Aug. 4, 1908.

Application filed December 23, 1904. Serial No. 238,058.

To all whom it may concern:

Be it known that I, EDWARD D. MEIER, a citizen of the United States, residing in the city, county, and State of New York, have invented certain new and useful Improvements in Superheaters, of which the following is a full, true, and concise specification.

This invention relates to superheaters and their relation to steam generating apparatus, and the invention consists in the features of structure, relative arrangement and disposition of the parts and their mutual operation, as will be fully described hereinbelow and more particularly pointed out in the accompanying claims.

In the accompanying six sheets of drawings forming a part hereof, Figure 1 is a front elevation of a steam generating apparatus including a superheater embodying my invention, Fig. 2 is a vertical transverse sectional view of the same on the line 2—2 of Fig. 3, Fig. 3 is a vertical longitudinal section on the line 3—3 of Fig. 1, showing parts in elevation, Fig. 4 is an enlarged plan view of a valve mechanism with parts in elevation and parts in section, Fig. 5 is a similar enlarged end elevation of the same apparatus with parts in section, Fig. 6 is a vertical longitudinal section of a modified form of my invention, Fig. 7 is a detail of valve mechanism for use with the structure of Fig. 6, Fig. 8 is a vertical longitudinal sectional view of a superheater, illustrating a number of U-tubes, in elevation, Fig. 9 is an end elevation of the superheater of Fig. 8, partly in section to illustrate the interior construction of the head, Fig. 10 is a vertical longitudinal sectional view of a modified form of superheater with the U-tubes shown in elevation, and Fig. 11 is an end elevation of Fig. 10 with the hand-hole coverings removed.

Referring first to Figs. 1 to 5, the steam generating apparatus is comprised of a water receptacle or boiler drum A provided at opposite ends with hollow water legs B connected with each other by means of a number of water tubes C. The legs B are supported upon suitable foundations so disposed that the water receptacle A is approximately horizontal although slightly inclined from front to rear, as shown in Fig. 3 and as customary in boiler construction. The water receptacle is surrounded by a walling of masonry built up around it so as to provide the usual fire box D with its flues or passages for the escape of the combusted gases. The

path of the latter may be traced as follows:—from fire box D rearwardly in the direction of the arrows, through passage marked E, then upwardly and forwardly through the series of water tubes C, then upwardly and again rearwardly through an upper fire gas passage marked F and from thence upwardly into a stack not shown, but connected with the structure at the point marked G. These passages are separated by the masonry in such manner that all of the fire gases from the fire chamber D must pass continuously through them, the upper and lower tiers of fire brick C' and C² being formed as shown, for this purpose. The upper passage F occupies the entire width from side wall to side wall of the structure and a portion of the upper boundary of the said passage F is formed by the lower half of the drum A, whereby the latter is also heated. The upper side of the drum is covered with a layer of lagging, indicated in Figs. 2-5 by the letter H.

Above the structure necessary to the performance of the above functions, a superstructure 1 is provided, either by means of a continuation of the masonry walls above referred to or by means of a separate structure of other material superposed thereon. The function of this superstructure is to provide an interior chamber 2 above and around the water receptacle with communication with the fire gas passage F on one or both sides of the drum, and the chamber 2 may be of any suitable dimensions with respect to the remainder of the apparatus but is preferably of about the proportion shown in the drawing and located near to the steam delivery pipe 3 of the water receptacle. An aperture 4 is provided in the wall of the chamber, preferably that wall which is proximate to the said steam delivery pipe, and a superheater, presently to be described, is mounted in this aperture with its tubes extending within and practically filling the entire upper portion of the said chamber, the superheater being in this manner disposed above the water level, indicated by a', Fig. 2, in the water receptacle.

The communication between the superheater chamber and the fire gas passage F, which as above stated may be on one or both sides of the drum, is controlled by suitable valve mechanism located in the region of the junction of said chamber and passage, this mechanism being preferably though not necessarily operable from the exterior of the

structure, and in cases where the communication between the chamber and the passage is on both sides of the boiler drum, the valve mechanism is double and capable of conjoint operation in various manners from the exterior of the structure. The function of the valve mechanism is to form a closure for the said superheater chamber shutting it off entirely from the fire gas passage and consequently from the heat of the same, or for causing the said chamber to form a virtual section of said passage interposed in the flow of gases therethrough, or in intermediate positions for allowing but a portion of said gases to flow through the chamber and its superheater as a by-pass, in this manner enabling a nice regulation of the degree of superheat to be obtained. The specific construction of the valve mechanism to accomplish this result is capable of considerable variation from that shown in the drawings and about to be described, as will presently appear. As shown in Figs. 1 to 5, the valve mechanism consists of a pivoted baffle or valve plate 9 mounted to swing from vertical to horizontal position within a framework, the latter being suitably built into or attached to the interior of the chamber walls so as to cooperate with the said plate in either of its extreme positions to form a continuous imperforate partition. The framework is formed of a horizontal frame piece 5 supported on three sides by the masonry walls and on the remaining side, which is adjacent drum A, by means of a projection or ledge 6 secured to the said drum. At the central portion of the frame piece 5 an upper and a lower frame piece, respectively designated 7 and 8, are secured so as to extend in a vertical direction and these frame pieces also serve as a support for fixed baffle plates 10 and 11, respectively disposed above and below the drum A in substantially the same plane as said vertical frame pieces 7 and 8. In one or the other of these frame sections where they are united, journal apertures are provided for the transverse axle of the swinging plate 9. As shown herein, the horizontal section (Fig. 5) contains such journal seats and also provides a housing or gear casing 12 into which the said axle protrudes. A worm gear 13 is fast on this axle within the casing and is engaged by a worm 14 on shaft 15, which latter extends forwardly through the structure to the front of the boiler where it is geared with a similar shaft extending from the gear casing of the valve mechanism on the other side of the drum, so that both of the plates 9 may be operated simultaneously and equally. The gearing for this purpose is clearly shown in Fig. 1. When placed in its position substantially parallel with the passage F, the pivoted plate on each side of the drum cooperates with the lower portion thereof and with the horizontal frame piece 5 to provide

a continuous path for the fire gases through said passage, allowing none of the same to enter the superheater chamber 2. In its vertical position substantially at right angles to the passage F, the plate cooperates with the fixed baffles 10 and 11 and with the vertical frame pieces 7 and 8 to form a continuous baffle intersecting and obstructing the passage F and directing the gases thereof into and through the superheater chamber. In its intermediate positions, the heated gases may travel through both passages in multiple and by reason of the superior position of the said chamber the hottest gases will naturally rise into the same giving the highest efficiency to the superheater compatible with free escape of gases from the region of combustion.

While the above described apparatus is preferred, it should be observed that the fixed baffle plates as well as the framework referred to may be formed of masonry similar to the side walls, if desired, without changing the functions performed, and that the gearing for conjointly operating the pivoted plates may also be located wholly outside the structure.

The superheater as employed in the apparatus so far described is shown in enlarged scale in Figs. 8 and 9 and consists of a head 20 with a number of U-tubes extending rearwardly from the said head and disposed across the upper portion of the superheater chamber. An additional baffle plate 16 is pierced by the lower tiers of these tubes and is suitably supported, as for example by chains, in registry with the upper edge of the baffle plate 10 and frame pieces 7, 7, thereby constraining the gases traversing the chamber to pass twice through the superheater tubes, first in an upwardly and then in a downwardly direction. The head 20 fits in the aperture 4 above described, being provided with means not shown, whereby it is permanently retained therein, and the entire superheater is preferably inclined from horizontal so as to permit water of condensation therein to be drained either through the supply steam pipe into the water receptacle or through a special branch connection 21 which leads from the lowest point of the head 20 into the water receptacle and preferably debouches into the latter at a point below the water level therein. The head 20 is composed of two opposite and parallel side walls with integral flanges turned in the same direction and joined by a strap 23, as shown in Fig. 8, and the said side walls are also firmly reinforced by a plurality of hollow rivets or staybolts 24. The interior of the head is subdivided into a number of compartments by means of partitions 22 and the U-tubes join the several compartments in such manner that steam entering the steam inlet is constrained to pass through all

of the compartments successively before reaching the outlet, indicated at K. Thus, the U-tubes leading from the first compartment at the points marked *a* have their other ends opening in the next adjacent compartment at points marked *b*, and the tubes leading from this compartment at the points marked *c* open at their other ends at points marked *d* in the next succeeding compartment, and so on, so that the steam travels through sections of the tubes in alternation with the several compartments of the head. The partitions 22 are not required to be steam tight, inasmuch as the pressures on opposite sides of them are substantially equal, and they serve merely to contain and direct the travel of the steam, insuring that the steam from tubes of different temperature be thoroughly mixed in transit. Opposite each of the openings of the U-tubes hand-hole openings 25 are provided in the opposite head plate and removable closures 26 normally cover them, as shown in Fig. 8.

In Figs. 6 and 7 is shown a modification of the foregoing structure in which the superstructure is permitted to be of less vertical dimension and the valve mechanism is correspondingly modified. In these figures the superheater is composed of U-tubes so arranged as to straddle the top of the boiler drum or it is composed of two separate superheaters disposed above and on either side of the same.

The valve mechanism is mounted in a horizontal frame piece 5' with a depending vertical section which coöperates with two oppositely swinging valves 9', 9', the latter being capable of swinging from a horizontal to a vertical position and thereby constituting in the first instance a closure for the chambers and in the second instance a baffle for the passage F directing the gases therein upwardly and downwardly through the superheater chamber. The short vertical and fixed baffle plate 16' is supported around the lower tiers of the superheater tubes, in registry with the valve plates when in vertical position and constrains the hot gases to pass twice through the superheater tubes. The superheater of proper shape for this modification is shown in Figs. 10 and 11 and consists of a head 20' similar in structural formation to the head of the superheater previously described, the U-tubes of this form being disposed in pairs close together so that a single hand-hole opening 25' may be provided for two ends instead of for one only as has heretofore been the practice, and this arrangement of the tubes also permits free passage of the gases in the chamber 2 between them. In Fig. 11, the hand-holes 25' are shown open to indicate the connection of tubes within, but in operation the steam is of course confined within the head and entering as before at the coupling flange 30 travels

through tubes marked *l* into the next lower compartment and from thence through tubes *m* into the lowest compartment and from this compartment through tubes *n* into the next and so on through tubes *o* to the outlet 31. In the modified form of Fig. 6 the two superheaters may be arranged to receive saturated steam from the water receptacle in series or in multiple, as desired, and in this modification is also illustrated a different and simplified type of valve operating mechanism. The two pivoted valve plates 9', and 9' suspended from a common axis are connected with double chains 32 led over a roller and connected to a pull rod 33, whereby they may be raised or lowered, as desired. The chains of the valve mechanism on both sides of the drum may obviously be operated by a single pull rod.

In Fig. 7 the valve plates 92, 92 are mounted on parallel adjacent axes and geared together so that movement of one is imparted to the other through the gearing, thus requiring but a single chain for each side of the drum A.

When the apparatus of this invention is put into operation the valve mechanism is manipulated to close communication between the fire gas passage F and the superheater chamber 2, so that the gases from the fire will pass directly through the passage into the stack. At this time, moreover, water of condensation in the superheater may be drawn into the boiler drum by opening the cock in pipe 21, which cock, however, may remain open as long as the superheater is used. As soon as steam becomes generated and fills the superheater, the valve mechanism may be opened to any extent desired according to the degree of superheat required, and the fire gases in the passage F will be constrained to pass around the U-tubes of the superheater, as above described, the entire superheater chamber passage or by-pass receiving a constant supply of hot gases and offering no pockets for the same to lodge in and become dead.

Having described my invention, what I claim and desire to secure by United States Letters Patent, is:—

1. In a steam boiler, a water receptacle having a horizontal passage for fire gases extending longitudinally beneath and along the sides thereof, in combination with a structure forming a chamber over said receptacle having communication with said fire-gas passage on either side of said receptacle, a superheater contained within said chamber, and means for controlling said communication.

2. In a steam boiler, an approximately horizontal water receptacle, a plurality of water-tubes beneath the same and connected therewith, and a passage for fire gases between said receptacle and tubes, in combi-

nation with a structure providing a superheater chamber over said receptacle having communication on either side thereof with the said fire gas passage, and means for deflecting the fire-gases into and through said chamber.

3. In a steam boiler, a water receptacle and a passage for fire gases extending beneath and along the sides thereof and leading to the escape stack, in combination with a superheater chamber above said receptacle, having communication with said passage adjacent to the side of said receptacle and means for controlling said communication.

4. In a steam boiler, a water receptacle and a longitudinal fire-gas passage beneath the same leading to an escape flue, a superheater chamber over said receptacle, said chamber being independent of and isolated from said escape flue and having a communication with said passage, and means for closing said communication, in combination with a superheater in said chamber above the water level of said boiler and a drainage pipe from said superheater to a point below the water level in the said receptacle.

5. In a steam boiler, a water receptacle, a fire-gas passage beneath the same and a superheater chamber over said receptacle adapted for communication with said passage, in combination with valve mechanism and a single member to operate the same, said mechanism being adapted to isolate the chamber from the fire-gas passage or to interpose said chamber in the path of said fire-gases, according to the adjustment of the said operating member.

6. In a steam boiler, a water receptacle provided with a bank of water-tubes connected thereto, a superheater chamber above the waterline of said receptacle and a fire-gas passage between said chamber and the said bank of water-tubes, in combination with valve mechanism adapted to be operated to isolate said chamber from the said passage or to divert the gases in the latter into and through said chamber.

7. In a steam boiler, a water receptacle, a passage for fire gases and a structure forming a superheater chamber in communication therewith, in combination with valve mechanism pivoted in the region of the junction of said chamber and passage and adapted to constitute a closure for either, whereby the gases in said passage may be delivered to or excluded from said chamber.

8. In a steam boiler, a water receptacle, a passage for fire-gases and a structure forming a superheater chamber in communication with said passage, in combination with valve mechanism located in the communication dividing the same into entrance and exit passages for the chamber, and means for

operating said mechanism to cause it to close said entrance and exit passages or to intercept the said fire-gas passage to direct the gases into and through said chamber.

9. In a steam boiler, a water receptacle, a passage for fire gases and a structure forming a superheater chamber having communication with said passage, in combination with a pivoted baffle plate having its pivotal axis mounted in the region of the center of and across said communication and capable of swinging into said passage, the said plate being of such dimension relatively to said passage as to constitute an obstruction to the latter when in one position and to form a closure for said communication when in another position.

10. In a steam boiler, a water receptacle and a structure providing a fire gas passage and also a superheater chamber in communication with said passage, in combination with a plate pivoted in the region of the junction of said chamber and passage transversely to the latter, a fixed baffle plate within said chamber adapted to register with the pivoted plate when it is substantially perpendicular to said passage, and a superheater in said chamber disposed on both sides of said fixed baffle plate.

11. In a steam boiler, a water receptacle, a fire-gas passage beneath the same, a superheater chamber above the waterline of said receptacle having communications with said passage respectively on opposite sides of said receptacle and means for controlling said communications.

12. In a steam boiler, a water receptacle, a structure providing a passage for fire gases and a superheater chamber in communication with said passage on either side of said receptacle, in combination with pivoted valve plates on opposite sides of said receptacle controlling said communication and means for conjointly operating said plates from the exterior of the structure.

13. In a steam boiler, a boiler drum, a fire-gas passage beneath the same and a superheater chamber having communication with said passage, in combination with a framework supported within said communication and a valve pivotally mounted therein and adapted alternately to close said communication or to intercept the gases in said passage.

14. In a steam boiler, an approximately horizontal boiler drum and a structure providing a superheater chamber above said drum, a fire gas passage beneath the same, and a communication between said passage and chamber at the side of said drum, in combination with a substantially horizontal ledge or projection on the side of said drum, a framework supported by said ledge and by the wall of the inclosing structure, and a valve pivotally mounted in said frame to

close said communication or to act as a baffle directing the flow of gases in said passage into and through said chamber.

15. In a steam boiler, an approximately 5 horizontal boiler drum, and a structure providing a superheater chamber above said drum, a fire gas passage beneath the same, and a communication between said chamber and passage on either side of said drum, in 10 combination with a pivoted plate acting as a closure for said communication when in horizontal position, a fixed baffle in the cham-

ber above the drum, a second fixed baffle beneath the drum adapted to register with said plate when in vertical position, whereby the 15 flow of gases in said passage may be directed into and through said superheater chamber.

In testimony whereof, I have signed my name to the specification in the presence of two subscribing witnesses.

EDWARD D. MEIER.
